UNITED STATES PATENT OFFICE.

JAMES SERSON, OF BOSTON, MASSACHUSETTS, ASSIGNOR TO JAMES O. WHITTEN, OF SAME PLACE.

GALVANIC BATTERY.

SPECIFICATION forming part of Letters Patent No. 375,007, dated December 20, 1887.

Application filed July 6, 1887. Serial No. 243,508. (No model.)

To all whom it may concern:

Be it known that I, JAMES SERSON, of Boston, in the county of Suffolk, State of Massachusetts, have invented a certain new and useful Improvement in Galvanic Batteries, of which the following is a description sufficiently full, clear, and exact to enable any person skilled in the art or science to which said invention appertains to make and use the same, reference being had to the accompanying drawings, forming part of this specification, in which—

Figure 1 is a top plan view of my improved battery, the cover being represented as in position and clamped or secured; Fig. 2, a side elevation of the same; Fig. 3, a top plan view, the cover being represented as removed; Fig. 4, a vertical transverse section taken on line $x x$ in Fig. 3, and Fig. 5 an enlarged diagram showing certain details of construction.

Like letters of reference indicate corresponding parts in the different figures of the drawings.

My invention relates more especially to that class of galvanic batteries which are provided with feeders or re-enforcing cups; and it consists in a novel construction and arrangement of parts, as hereinafter more fully set forth and claimed, the object being to produce a more effective and otherwise desirable device of this character than is now in ordinary use.

The nature and operation of the improvement will be readily understood by all conversant with such matters from the following explanation:

In the drawings, A represents the inclosing jar, which is preferably composed of hard rubber, but may be made of glass or any other suitable material. This jar is provided with an annular projection, m, which is preferably formed integral with its bottom v and arranged concentrically with its walls, said projection being in the shape of a truncated cone in vertical cross-section and provided at its apex with a channel, b, extending its entire length.

A cylindrical amalgamated battery-zinc, B, provided with an upwardly-projecting arm, d, and a vertical opening through one of its sides, (shown by the dotted lines a in Fig. 2,) is disposed in the jar A, its bottom or lower edge being inserted in the channel b. This channel

is partially filled with mercury, t, in which the lower edge or portion of the zinc B is immersed when in position for use, the mercury being carried upward by capillary action and serving to constantly amalgamate the zinc, or restore it to its normal condition as the amalgam on its surface is destroyed by the corrosive action of the acidulated solution in which it is submerged.

A porous cup, C, composed of biscuit-porcelain or other suitable material, is placed centrally within the jar A, said cup being considerably less in diameter than the zinc B, and arranged concentrically therewith. Disposed within said porous cup there are three portable or detachable re-enforcing cups, E F G, and also a cylindrical carbon, D, provided with transverse slots or openings r in its lower portion or edge, and with an upwardly-projecting arm, f. The carbon is considerably less in diameter than the porous cup and is concentrically arranged therewith. Three sockets, y, for receiving the cups E F G, are formed on the bottom of the porous cup C, said sockets being preferably grouped around its center, as shown in Fig. 3.

The re-enforcing cups are porous, being composed of biscuit-porcelain or similar material, and are of such size that when placed in position in the sockets of the cup C a chamber or space of suitable dimensions to receive the solution used in said last-named cup will be left between them and the carbon D. The cup E is provided with a series of lateral perforations, g, through which the solution in the porous cup may freely pass. A screw-cap, H, is attached to each of the arms f d, in which the conducting-wires l w are respectively secured in the usual manner.

A cover, J, provided with a downwardly-projecting annular flange, k, at its periphery, is fitted to the jar A, said cover having openings through which the arms f d protrude when the cover is in position on said jar. A clamping-bar, K, provided with a downwardly-projecting arm, h, at either end having an inwardly-projecting hook, j, is employed for securing the cover in position on the jar A. A lever, L, is centrally pivoted to the bar K, said lever being provided with a cam, p, which is

fitted to work in an elongated slot, *q*, in said bar and press upon the cover *J* when the lever is depressed. Projecting laterally from the jar *A* near its top there are two lips or flanges, *u*, one at either side thereof, with which the hooks *j* on the arms *h* of the bar *K* are respectively adapted to engage, and in attaching the cover *J* to said jar the lever *L* is raised and said hooks adjusted to engage said lips, after which the lever is depressed, thereby bringing the cam *p* into forcible contact with the top of the cover and locking it in position in a manner which will be readily obvious without a more explicit description.

15 The mechanical parts of my improved battery having been constructed and arranged as shown and described and the channel *b* filled with mercury, the screw-caps *H*, clamping-bar *K*, and cover *J* are removed and the porous cup *C* filled with the following galvanic element or solution, *M*.

(For convenience of reference I will designate the solution used in the porous cup *C* as the "inner solution," and that used in the annular cell or chamber *z*, between said cup and the jar *A*, as the "outer solution.")

Formula for the inner solution.—Take two gallons of water, one gallon of sulphuric acid, one and one-half gallon of nitric acid, three 30 pounds and four ounces of chromic acid, and nine pounds of bichromate of potash. Mix these ingredients in any suitable vessel, and when thoroughly dissolved and incorporated use a sufficient quantity of the element or solution thus formed to fill the porous cup containing the carbon *D* and cups *E F G*. When the porous cup has been filled, as described, the annular cell or chamber *z*, containing the zinc *B*, between the porous cup and walls of 40 the jar *A*, is then filled with the following galvanic element or solution, *N*.

Formula for the outer solution.—Take one gallon of sulphuric acid and six gallons of water. Mix these ingredients in any suitable 45 vessel and use a sufficient quantity of the element or solution thus formed to fill the cell or chamber *z* containing the zinc *B*. After the cell or chamber *z* has been filled with the last-named solution, as described, the perforated 50 re-enforcing cup *E* is filled with bichromate of potash, the cup *F* with nitric acid, and the cup *G* with sulphuric acid. The cover *J* is then replaced and secured by the clamping-bar *K*, and lever *L* and the screw-caps *H*, carrying the wires *l w*, attached to the arms *d f*, the battery being now in operative condition. When the battery is to be moved while in use, or if employed where there is more or less motion, as in lighting railway-cars, &c., the cover 55 *J* is provided with rubber packing-rings on its under side adapted to fit tightly around the arms *d f* and also press upon the upper edges of the jars, zinc, and carbon, thereby preventing the solutions in the battery from being spilled or accidentally mixed with each other.

The object of the acids and bichromate of potash which are respectively placed in the

cups *E F G* is to re-enforce or feed the inner solution in the porous cup *C*, and thereby maintain its strength.

I have found in practice that the use of an inner solution comprising water, nitric acid, sulphuric acid, bichromate of potash, and chromic acid in combination with an outer solution comprising water and sulphuric acid in about the proportions and compounded substantially as described effectually prevents polarization and the precipitation or deposit of sulphate of zinc and the sesqui-oxide or oxide of chromium, or "chromic alum," on the carbon or zinc of the battery. I have also found that the use of free mercury, *t*, in the channel *b* will keep the zinc *B* thoroughly amalgamated, and thus prevent its premature destruction by the corrosive action of the acidulated solution 85 in which it is submerged.

The cups *E F G*, being portable, may be easily replaced when broken or removed to be cleansed or filled without interfering with the action of the battery.

I do not confine myself to the proportions stated in formulating the galvanic elements or solutions *M N*, as these may be varied considerably without materially changing their nature or the results attained by their use; nor to arranging the cups *E F G* in any special manner within the porous cup *C*, as their arrangement is immaterial, excepting as a matter of convenience. Neither do I confine myself to making said re-enforcing cups cylindrical, 95 as they may be made of any suitable form or size; nor to making the jar *A*, projection *m*, cup *C*, zinc *B*, and carbon *D* of the precise forms or styles shown and described, as these parts may be varied considerably in that respect 100 without departing from the spirit of my invention; nor to the use of three re-enforcing cups, as one or more may be used, as required; nor to the use of the sockets *y* for holding the re-enforcing cups, as any suitable means may be 105 employed for that purpose; nor to the use of the mechanical parts of the battery with solutions compounded precisely as described, as said parts are adapted for use with any suitable liquid galvanic elements or solutions; nor 110 to the use of the solutions with the mechanical parts described, as said solutions are well adapted for use in batteries differently constructed.

As I have made the galvanic elements or solutions respectively designated as "the inner solution" and the "outer solution" the subject-matter of another application for Letters Patent, Serial No. 243,942, I do not herein claim the same, broadly.

Having thus explained my invention, what I claim is—

1. In a galvanic battery of the character described, the jar *A*, having the interiorly-disposed annular projection *m*, provided with the channel *b* for containing free mercury with which to keep the zinc *B* amalgamated, substantially as set forth.
2. In a galvanic battery of the character de-

scribed, the combination of the jar A, provided with the channeled projection *m*, the porous cup C, provided with the sockets *y*, the zinc B, provided with the arm *d*, the carbon D, 5 provided with the arm *f*, the portable or detachable cups E F G, means for connecting the wires *l w* to the zinc and carbon, a cover for the jar A, and means for securing the cover on said jar, substantially as described.

10 3. In a galvanic battery of the character described, the jar A, provided with the channeled projection *m*, the zinc B, having its lower portion or edge inserted in the channel of said projection, the porous cup C, centrally disposed in the jar A, one or more portable or detachable re-enforcing cups disposed within said porous cup, and the carbon D, disposed between the re-enforcing cup or cups and the walls of said porous cup, in combination with 15 an acidulated solution in the porous cup, an acidulated solution in the chamber between the porous cup and walls of the jar A, the mercury, *t*, in the channel *b*, and a re-enforcing mate-

rial or materials in the re-enforcing cup or cups, substantially as set forth. 25

4. In a galvanic battery of the character described, the inclosing jar A, provided with the lips *u* and projection *m*, having the channel *b*, the zinc B, provided with the arm *d* and having its lower portion or edge inserted in 30 said channel, the porous cup C, centrally disposed in said jar and provided with sockets *y*, the re-enforcing cups E F G, disposed in said porous cup and secured by said sockets, the carbon D, provided with the arm *f* and disposed between said re-enforcing cups and the walls of the porous cup, the clamping-bar K, provided with the cam-lever L, arms *h*, and hooks *j*, and the screw-caps H, all constructed, combined, and arranged substantially as shown 35 40 and described.
